UNITED STATES PATENT OFFICE.

CLARENCE LILE, OF GRANITE CITY, ILLINOIS, ASSIGNOR TO SUPERIOR PRODUCTS COMPANY, OF GRANITE CITY, ILLINOIS, A CORPORATION OF ILLINOIS.

BOX-LINER.

1,222,221.

Specification of Letters Patent.

Patented Apr. 10, 1917.

Application filed March 29, 1916. Serial No. 87,420.

To all whom it may concern:

Be it known that I, CLARENCE LILE, a citizen of the United States, residing at Granite City, in the county of Madison and State of Illinois, have invented certain new and useful Improvements in Box-Liners, of which the following is a full, clear, and exact description, reference being had to the accompanying drawings, forming a part hereof.

My invention has relation to improvements in box linings; and it consists in the novel features of construction more fully set forth in the specification and pointed out in the claims.

The present invention is directed particularly to the lining of tobacco and cigar boxes which are generally lined with a thin sheet of veneer of wood or suitable composition, the object sought being to secure the lining to the box walls in such a way as to hold the same against longitudinal and rotary displacement, and further to secure it in such a way as to prevent the lining from detaching itself or becoming loose as a result of contraction or expansion brought about by variations in atmospheric conditions. The lining as constructed may of course be applied to boxes of any kind, the same not being necessarily restricted in its application to tobacco and cigar boxes, the latter being but a single example of container in which the lining may be used to advantage. The details of the invention and the several advantages accruing therefrom will be apparent from the following description considered in connection with the accompanying drawings in which—

Figure 1 represents a perspective of a conventional tobacco box with my invention applied thereto, with parts broken away and lid removed; Fig. 2 is an elevation thereof, the lid being shown in dotted position; Fig. 3 is an end view of the wall liner showing the terminal tongue sections at the ends of the meeting edges of the sheet forming the liner; Fig. 4 is an elevation of the bottom of the wall liner showing the locking tongue sections, and an edge view of the bottom or end liner showing the marginal dove-tail recess for receiving the tongue; Fig. 5 is a top plan of a portion of the end liner showing the marginal dove-tail recess; Fig. 6 is an inside elevation of the upper terminal of the wall-liner showing the seam formed by the

meeting edges thereof and the clenchers or prongs punched from the wall of the box and folded over the liner; Fig. 7 is a top edge view of Fig. 6; and Fig. 8 is a cross-sectional detail on the line 8—8 of Fig. 6.

Referring to the drawings, 1 represents a conventional prismatic sheet metal tobacco box closed at one end and provided with a removable cover or lid L at the opposite end (shown dotted Fig. 2), the corners of the box being preferably rounded as well understood in the art. The closed end or bottom of the box is lined with a sheet 2 of wood veneer or other material, the edge of said end liner being provided at a convenient point between two adjacent corners of the box, with a marginal dove-tail recess r the sides of which are bounded by sloping or wedge faces w inclining inward, that is to say downward toward the bottom face of the liner 2. The wall liner comprises a pliable veneer or equivalent sheet 3 of sufficient dimensions to cover the entire inner surfaces of the inclosing walls of the box, the lower corners of the sheet, that is to say the corners at the meeting ends of the edges e, e, and bottom edges h, h, (Fig. 4) being provided with tongue sections t, t, which jointly form a single tongue insertible into the dove-tail recess r, the outer sides of the respective tongue sections having sloping faces w', w', for engaging the faces w, w, of the recess r.

It will be readily seen from the foregoing that upon insertion of the tongue sections t, t, into the recess r, the coöperating faces w, w', of the recess r and tongue sections respectively will cause the tongue sections to be forced or drawn together, thereby drawing together the edges e, e, and forming a tight or closed seam s between the free meeting ends of the sheet 3. Opposite the seam s the upper terminal of the box wall is afterward slit to a suitable depth, thus permitting the bending therefrom of suitable prongs or clenchers 4, 4, which are folded over the liner 3 on opposite sides of the seam s, thus clenching the wall liner to the box wall at a point opposite its interlocked connection with the end or bottom liner 2. The bending or folding of the prongs 4, 4, in the manner indicated results in the formation of a V-shaped notch V along the upper edge of the box wall, but this is subsequently covered by the lid L so as to be concealed from view.

- Thus it will be seen that the wall liner 3 is anchored at one end to the liner 2, the dove-tail recess *r* holding the wall liner against radial movement or movement inwardly away from the box walls, the wedge shaped faces *w*, *w'*, on the other hand preventing an opening of the seam *s* or parting of the edges *e*, *e'*; and the clenches 4, 4, locking the upper end of the wall liner to the box walls against longitudinal displacement and displacement inwardly or away from the walls. The wall liner will thus remain anchored to the walls of the box irrespective of any shrinkage or contraction it may undergo as a result of changes in atmospheric conditions. To permit folding of the prongs 4, 4, over the liner 3, the corners of the latter necessarily must be cut to conform to the V-shaped notch V (Fig. 6).
- I do not of course wish to restrict the application of the invention to tobacco or cigar boxes, or to sheet metal boxes or to boxes of a prismatic form. The invention may be applied to any lined receptacle whatsoever and of any form; neither do I wish to be limited to any specific material entering into the construction or composition of the liners.

Having described my invention what I claim is:

1. A box wall-liner comprising a flexible sheet insertible into the box and having its opposite ends brought into abutting relation, and means in the box at one end of the

seam thus formed for drawing said ends into firm engagement.

2. In combination with a box closed at one end, an end liner provided with a marginal dove-tail recess or groove, a wall-liner comprising a flexible sheet disposed along the inner walls of the box and proportioned to have its free ends come into opposed relation when the sheet is deposited in the box, and suitable tongue sections at adjacent terminals of the free ends aforesaid jointly forming a tongue engaging the dove-tail recess aforesaid.

3. In combination with a box closed at one end, an end liner provided with a marginal dove-tail recess having side walls sloping toward the base of the recess, a wall-liner comprising a sheet disposed along the inner walls of the box and proportioned to have its free ends come into contiguous and opposed relation when the sheet is deposited in the box, and suitable tongue sections at adjacent terminals of the free ends of the wall liner forming jointly a tongue insertible into the recess aforesaid, the sides of the tongue being beveled to conform to the slope of the sides of the recess.

In testimony whereof I affix my signature, in presence of two witnesses.

CLARENCE LILE.
